Inventor:
Louis T. Frederick
By Cheever & Cox Atty.

UNITED STATES PATENT OFFICE.

LOUIS T. FREDERICK, OF VALPARAISO, INDIANA, ASSIGNOR TO FIBROC INSULATION COMPANY, OF VALPARAISO, INDIANA, A CORPORATION OF INDIANA.

TELEPHONE DIAPHRAGM.

Application filed April 24, 1924. Serial No. 708,668.

My invention relates to telephones, especially of that type in which the diaphragm in the receiver or transmitter is of electro-magnetic material, and is consequently responsive to the fluctuations in the magnetic field in which it is placed. The object of the invention is to render the diaphragm more sensitive than the types heretofore known. In order to avoid the effect of hysteresis it is common to employ soft steel or similar metal approximately .010 inch thick, varnished for appearance and for protection against rust. According to my invention I employ a composite diaphragm composed of a much thinner sheet of metal reinforced by means of a lighter material, for example, synthetic resin condensate.

I accomplish my object by the manner illustrated in the accompanying drawings, in which—

Figure 1 is an axial sectional view of a telephone receiver in which a diaphragm embodying my invention is mounted.

Figure 2 is a cross section of a diaphragm embodying my invention showing the same in lenticular form.

Figure 3 is a cross section of a diaphragm of uniform thickness.

Figure 4 is a bottom plan view of the magnet shown in Figure 1; and

Figure 5 is a face view of a diaphragm embodying my invention, a portion of the outer surface being broken away to show internal construction.

Like numerals denote like parts throughout the several views.

While the form of mounting for the diaphragm may be greatly varied I have shown a mounting consisting of a casing 1 and a screw cap 2 between which the diaphragm is clamped when the parts are assembled. Mounted within the casing are means for producing a fluctuating magnetic field. As these are known it will be sufficient for the present purpose to say that in the illustrated construction electro-magnetic windings 4, 4 are employed to magnetize cores 5, 5 which are placed in juxtaposition to the diaphragm in accordance with common practice.

Now referring to the diaphragm which constitutes the essence of the invention, I

provide a thin disc 6 of soft iron or other suitable metal, the same having a number of holes 7 punched therein at various points throughout its extent. This disc instead of being of ordinary thickness is much thinner, for example .002 or .003 inch, although I do not wish to be understood as confining myself to discs as thin as this. This metal disc is embodied in plastic material 8 of a character lighter and more resilient than the metal disc. For this purpose I prefer to use a synthetic resin condensate. Such condensates are commonly produced chiefly from phenol and formaldehyde and such material is sometimes known as bakelite. This condensate is at first plastic and I produce the composite diaphragm by molding the thin disc within the condensate. The molding action is accomplished usually under heat and pressure and during the molding process the condensate will fill the apertures in the metal disc and thus produce a diaphragm which is a unitary structure, but is provided with a magnetic core.

While I prefer the lenticular form shown in Figure 2—that is, a diaphragm having the form of a thin double convex lens, it is possible also to employ the flat form shown in Figure 3. In this case the condensate 9 will be of uniform thickness.

As the condensate is resilient and much lighter than metal my composite diaphragm vibrates much more readily than one made entirely of metal and hence it is much more sensitive.

While I have shown the metal core as extending to the periphery of the disc, it may be of smaller diameter. For example it may be confined to the central portion, near the magnetic pole pieces 5, where the lines of magnetic force are most concentrated.

It will be understood that the term "telephone" as herein employed is intended to include loud speakers and other instruments operating upon the electromagnetic principles above described.

I do not herein claim the idea of a lenticular diaphragm broadly, for it forms the subject of a separate application filed by me on even date herewith.

Having thus described my invention, what

I claim as new and desire to secure by Letters Patent is:

1. In a telephone, a composite diaphragm composed of a thin sheet of metal and a layer of synthetic resin condensate rigidly secured thereto for reinforcing it, and electromagnetic means operable on said sheet for vibrating it.
2. In a telephone, a composite diaphragm

disc having a central core of thin sheet metal 10 embodied in a resilient body of hardened plastic material of lenticular form whereby the diaphragm as a whole is thinner at the periphery than at the central portion.

In witness whereof, I have hereunto subscribed my name.

LOUIS T. FREDERICK.
